UNITED STATES PATENT OFFICE.

HENRY M. FISK, OF WHEATON, ILLINOIS.

COMBINATION DROP AND JACK FOR TELEPHONE-SWITCHBOARDS.

SPECIFICATION forming part of Letters Patent No. 699,619, dated May 6, 1902.

Application filed June 22, 1900. Serial No. 21,235. (No model.)

To all whom it may concern:

Be it known that I, HENRY M. FISK, a citizen of the United States, residing at Wheaton, in the county of Du Page and State of Illinois, have invented certain new and useful Improvements in a Combined Drop and Jack for Telephone-Switchboards, of which the following is a full, clear, concise, and exact description.

10 My invention consists of, first, an improved and novel combination of parts for the restoration mechanically of the indicators of telephone-lines by the act of inserting the plugs in the line-jacks, and, secondly, in certain 15 new configurations and the organization of the parts of said indicators, whereby the cost of manufacture is reduced and they are rendered more substantial than heretofore.

In the accompanying drawings, Figure 1 represents diagrammatically the principle of 20 my restoring device. Fig. 2 shows a modified form of the same. Fig. 3 shows additional modifications. Fig. 4 shows a sectional view of the complete drop and jack and my 25 particular construction of the same. Fig. 5 represents a front view of the devices shown in Fig. 4. Fig. 6 represents a back view of the same. Fig. 7 illustrates the restoring-link in detail. Fig. 8 is a sectional view and shows 30 the night-bell contacts. Fig. 9 is a top view of the device, and Fig. 10 shows the electrical circuit of the coil and springs.

Like letters refer to like parts in all figures.

Referring to Fig. 1, a' represents a shutter 35 of a telephone-indicator pivoted at a^2 . b' is a detent pivoted at b^2 and adapted to engage with shutter a' and retain it in its normal position. C is a switchboard-plug adapted to be inserted in the socket D. A suitable slide 40 E is adapted to move back and forth horizontally. One end e^2 of the said slide E is so formed as to engage with tip c^3 of the plug C, whereby it is caused to travel in a horizontal direction with the plug when the same is inserted in the socket D. The other end e^3 of the said slide E is so formed up that it engages with the shutter a' and causes it to rise to the vertical position and engage with the detent b' when the said slide E is caused to 45 move in the proper horizontal direction by the insertion of the plug C. The modification of this slide shown in Fig. 2 consists

in the bend in the slide E, (shown at e^5), which when the slide is actuated by the plug C tends to give the end e^3 an upward movement by riding on the bearing e^4 .

The modification shown in Fig. 3 takes advantage of the forms in Figs. 1 and 2 and also utilizes the handles of the plug to further increase the movement upward of the end e^3 . Plug C has its handle beveled at c^2 to an angle of approximately forty-five degrees. The bearing e^6 serves to steady the slide, that the end e^3 will remain engaged with the tip of plug throughout its travel. The bend e^5 and bearing e^4 serve the same purpose as explained in Fig. 2.

Fig. 4 shows in detail the means by which I adapt my restoring device for use in telephone-switchboards. The core x is inclosed 70 in the winding y and is rigidly fastened to the end w^3 of piece W, which is of iron and serves as both a frame upon which all other parts are mounted and as the return-piece of the magnet-core x . Piece w is turned up at 75 w^2 and has the extensions w^4 and w^5 formed upon it, from which is suspended the armature V.

As indicated in Fig. 6, the end w^2 is cut away in such a manner that the end of core 80 X is clear of it at all points, and the magnetic path of the least resistance from the core X to the piece w^2 is through the armature V, which is thus controlled by the winding Y when said coil is energized.

The piece W, as is shown in Fig. 9 at w^5 85 w^5 , extends out beyond the body of the device to form two extensions, which fit into grooves g in the frame of the switchboard-cabinet, as shown in Fig. 6, to hold the device in place. The armature V carries the detent b' , to which it is rigidly fastened. On the face of the end w^3 is mounted a block of insulating material s , which in turn carries the number-plate R of the drop and the pivots a^2 , upon which the shutter a' swings. On the front part of the lower face of piece w is mounted the block of insulating material T, in which is fitted the sleeve D of the jack. The face t^4 of the block T, Fig. 4, serves the 90 same purpose as the bearing e^4 in Figs. 2 and 3. The piece w is cut away at this point, as shown in detail at w^6 in Fig. 7, and is adapted to form a guide for the slide E to hold the 95 100

same in place. The slide E bears against the piece w at e⁶, which is the equivalent of the bearing e⁶ in Fig. 3. A button of insulating material e⁷ is mounted in the end e² of the 5 slide E in such a manner as to insulate the slide E from the tip c³ of the switchboard-plug when the same engages with the slide to operate the same.

At the rearward part of piece w is mounted 10 an insulating-block u, carrying the springs f¹ f² of the jack and also the connector d² of the sleeve D. The spring f² is adapted to engage with the tip c³ of the plug C and to be moved by the same out of contact with 15 spring f¹.

The winding of the coil y is connected with the springs f¹ and f² and the sleeve-connector d² in such a manner as to make the well-known circuit for switchboard drops and 20 jacks and which is illustrated diagrammatically in Fig. 10.

The night-bell contacts and circuit are shown in detail in Fig. 8. In the insulating-block S a recess is cut to permit of the extension a³ of shutter a' to pass. In the path 25 of the extension a³ at a suitable point is placed a small rod a⁴, which acts as a stop for the shutter a' and also as one contact of the night-bell circuit. The shutter a' serves as 30 the other contact, and when it falls closes the circuit and causes the bell to ring in the well-known way.

Having thus fully described my invention in full, what I desire to secure and protect by 35 Letters Patent is—

1. In a combined indicator and jack for telephone-lines, the combination of a socket, a suitable plug adapted to enter said socket, a drop-shutter in close proximity to said socket 40 and a slide adapted to engage with the tip of said plug to be moved horizontally thereby and adapted to coöperate with the said drop-shutter to restore the same; said slide being so formed that a vertical movement is im- 45 parted to the end coöoperating with the drop-shutter when said slide actuated by said plug rides horizontally over a suitable bearing, whereby the drop-shutter is restored to its normal position with greater certainty.

50 2. The combination of a drop, a device con-

structed and arranged to be moved bodily by and travel with a plug and means for simultaneously raising said device to close the drop.

3. The combination with a jack-socket and a drop, of a longitudinally-movable slide having a portion to be engaged by a plug, and a cam for causing the slide to rise and restore the drop when the plug is moved longitudinally in the jack-socket. 55

4. The combination with a drop, a jack-socket and a front piece having a slot, of a slide adapted to be moved by a plug, projecting through the slot and having a cam to engage the wall of the slot and raise the slide to restore the drop. 60

5. The combination with a drop and jack-socket, of a slide projecting beyond the drop and adapted to receive it when it falls, an arm depending from the slide into the jack-socket and adapted to be actuated by a plug and a cam to effect the elevation of the slide to restore the drop. 65

6. In a combined indicator and jack device for telephone-lines, the combination with the jack having a socket, of a suitable plug adapted to enter said socket, a drop-shutter pivoted upon the front of said device above the socket and in close proximity thereto, a longitudinally-movable slide mounted in said device above the socket and having a downwardly-turned end extending into the path of the plug when the plug is inserted in the socket, the outer end of said slide being turned upwardly so as to stand in front of said drop-shutter, whereby when the drop-shutter is 70 down and the plug is inserted in the socket, its tip engages the downwardly-turned end of the slide and causes the slide to travel inwardly with the plug while the said outer upturned end of the slide engages the drop-shutter and restores the same, substantially as described. 75

In testimony whereof I have signed this specification in the presence of two subscribing witnesses.

HENRY M. FISK.
